LOOP-TAKER MECHANISM FOR SEWING MACHINES

Arthur N. Hale, Bridgeport, Conn., assignor to
The Singer Manufacturing Company, Elizabeth, N. J., a corporation of New Jersey

Application August 22, 1941, Serial No. 407,842

36 Claims. (Cl. 112—159)

This invention relates to improvements in loop-taker compensating mechanisms for sewing machines having laterally vibratory needles, as in zigzag stitching machines.

Various expedients have been heretofore devised to insure that the looper or loop-taker complementary to the laterally vibratory needle of a sewing machine is adapted to seize needle-thread loops in the spaced loop-presenting positions of the needle. A common practice has been to accelerate and retard the rotation of a loop-taker for this purpose. Another well known form of construction involves reciprocating the loop-taker in a right line or vibrating the loop-taker in an arcuate path in order to position the loop-taker properly for seizing the needle-thread loops of a laterally vibrated needle. These prior constructions inherently impose definite limitations in the possible speeds of operation of the machines, in the width of bight of the zigzag stitches formed, and in the number of needles that may be employed.

The loop-taker compensating mechanism of the U. S. patent to R. M. Sharaf, No. 1,466,149, Aug. 28, 1923, indicates an effort to overcome some of these prior difficulties by the provision of means for imparting orbital compensating movements to a loop-taker. However, this prior construction contained the speed-limiting features of intermittently shifting the loop-taker in its orbital path of movement and of imparting variable speed rotations to the loop-taker. Furthermore, this prior construction contained no provision for adapting the loop-taker compensating mechanism to variations in the amplitude of lateral vibration of the needle.

The present invention has for its primary object to provide a loop-taker compensating mechanism which is particularly well adapted for high speed operation. Another object of the invention is to provide a high speed loop-taker mechanism adaptable to compensate for needle vibrations of variable amplitude.

The invention has also for its objects to provide improved rotation-restraining and mechanical-opener means for the thread-carrier journaled in a loop-taker having needle-vibration compensating movements. Other and more specific objects of the invention will be apparent from the following description and claims.

These objects are attained by mechanism hereinafter described in connection with the accompanying drawings which illustrate a preferred embodiment of the invention and in which:

Fig. 1 is a front side elevation of a two-needle

sewing machine containing the improved loop-taker mechanism. Fig. 2 is an enlarged bottom plan view of the loop-taker end portion of the machine. Fig. 3 represents an enlarged vertical section taken transversely of the bed-plate of the machine and substantially through the axis of rotation of the right hand loop-taker. Fig. 4 represents an enlarged vertical section of the right hand loop-taker mechanism and taken lengthwise of the bed-plate of the machine. Fig. 5 is an enlarged top plan view of the right hand loop-taker bracket or hook-saddle, with the loop-taker omitted and its shaft shown in horizontal section taken through the opener-actuating eccentric portion thereof. Fig. 6 is a fragmentary top plan view of the loop-taker bracket, with the loop-taker shaft and its bearing-bushing cut away on substantially the line 6—6 of Fig. 4. Fig. 6a represents a disassembled perspective view of the upper end portion of the carrier-member employed for adjustably supporting the upper loop-taker shaft bearing-member. Fig. 7 is a perspective view of one of the loop-takers, including the loop-taker shaft bearing-member, the thread-carrier rotation restraining means and the mechanical opener.

Referring to the drawings, the sewing machine has a frame comprising a frame-bed 10, from one end of which rises the tubular standard 11 of a bracket-arm 12 overhanging the frame-bed lengthwise thereof, said bracket-arm terminating at its free end in a head 13. The frame-bed 10 has depending front and rear side-flanges 14 integral with end-flanges 14', said flanges providing a plurality of machine supporting feet 15. The frame-bed flanges have an external substantially horizontal rib 16 below the upper or work-supporting face of the frame bed, whereby the machine may be supported in the usual opening of a power-table.

Rotatably journaled in the bracket-arm 12 to extend lengthwise thereof is a horizontally disposed main actuating shaft 17, carrying at one end thereof the usual belt-pulley 18. At its opposite end, the main shaft 17 is operatively connected for vertically reciprocating two needles 19, 20, which are preferably disposed abreast with respect to the direction of feed of the work. The needles, 19, 20, are vibrated laterally lengthwise of the bracket-arm 12 by operative connections with actuating mechanism which may be of any usual or suitable construction to effect the production of zigzag stitches. The specific form of needle-vibrating mechanism in part illustrated in

the accompanying drawings forms the subject of a separately filed patent application.

The present invention relates more particularly to the supporting and actuating mechanism for loop-takers disposed below the upper or work-supporting surface of the frame-bed 10 and complementary to the endwise reciprocatory and laterally vibratory needles 19, 20, in the formation of stitches.

Within the bracket-arm 12 of the machine, the main or arm shaft 17 carries a pulley 21 connected by a clip-belt 22 with a pulley 23 carried by a bed-shaft 24. The pulleys 21 and 23 are of equal size and thereby have the same angular velocity of rotation. The bed-shaft 24 is disposed substantially parallel to the arm-shaft 17 and is rotatably journaled in horizontally spaced bearing-bosses 25, 26 and 27 provided upon the bed-frame.

Secured upon the bed-shaft 24 for adjustment lengthwise thereof and between the bearing-bosses 25 and 26 of the frame-bed is the hub 28 of a spiral gear 29 in driving engagement with a spiral pinion 30. The gear 29 and the pinion 30 are proportioned so that the pinion 30 rotates twice for each rotation of the driving gear 29.

The driven pinion 30 has its hub secured by a screw 31 upon the lower end of a vertically disposed shaft-section 32; said shaft-section 32 comprising a lower or driving section of a flexibly jointed sectional loop-taker shaft. The shaft-section 32 is rotatably journaled in ball-bearings 33 and 34 disposed in vertically spaced relation in suitable recesses provided in a vertically apertured bearing lug 35. The bearing-lug 35 is integral with and depends from a horizontally flattened supporting plate 36 of a stationary loop-taker bracket 37. The front and rear side flanges 14 of the frame-bed are provided with inwardly extending and horizontally flattened ledges 38, and the loop-taker bracket-plate 36 is provided at the front and rearward ends thereof with a plurality of elongated slots 39 to receive screws 40 by means of which the bracket-plate 36 is secured to the ledges 38. The slots 39 are elongated lengthwise of the bed-frame 10 to provide for adjustment of the loop-taker bracket 37 longitudinally of the bed-shaft 24.

The loop-taker bracket 37 has an upper bearing-lug 41 disposed vertically above and spaced from the lower bearing-lug 35. The upper bearing-lug 41 is vertically apertured to provide a bearing-opening 42, in which is rotatably journaled a tubular carrier-member 43 having at its upper end a peripheral flange 44. The carrier-member flange 44 is rotatably supported upon a shoulder 45 formed by a counter-bore 46 provided in the upper portion of the bracket-lug 41. The carrier-member 43 has a reduced extension 47 disposed below the lower face of the upper bearing-lug 41; and secured by a set-screw 48 upon said reduced extension 47 of the carrier-member 43 is a spur-gear 49. The upper side face of the spur-gear 49 proximate to the bearing-lug 41 is preferably partly cut away to receive a washer 50 interposed between the spur-gear 49 and the flattened lower face of the upper bearing-lug 41. It will be understood from the foregoing description that the carrier-member 43 is restrained by its flange 44 and the spur-gear washer 50 from endwise movement in the bearing-lug 41.

The spur-gear 49 of the carrier-member 43 is in mesh with a smaller spur-gear 51 suitably se-

cured upon an upright counter-shaft 52 having its opposite ends rotatably journaled in the bearing-lugs 35, 41; a washer 53 being preferably disposed between the spur-gear 51 and the lower face of the bearing-lug 41. Secured to the counter-shaft 52 for rotation therewith is another spur-gear 54 in mesh with a spur-gear 55 suitably secured upon the upper end of the shaft-section 32 above the lower bearing-lug 35. The ratio of the speed-reducing gears 55, 54, 51 and 49 is such that the carrier-member 43 is rotated once for four rotations of the shaft-section 32, it being understood that the axes of rotation of the shaft-section 32 and of the carrier-member 43 are coincident.

The upper end face of the carrier-member 43 is recessed to provide a horizontal guideway which lengthwise extends transversely of the axis of rotation of said carrier-member. One side edge 56 of the guideway recess is undercut and its opposite side edge comprises a substantially vertical shoulder 57. Adjustably seated in said guideway of the sleeve 43 is a horizontally disposed peripheral flange 58 formed intermediate the ends of a vertically tubular bearing-member 59. The opposite sides of the bearing-member flange 58 are cut away to provide downwardly beveled and substantially straight guide-edges 60 and 61, of which the beveled guide-edge 60 slidably fits the undercut edge 56 of the carrier-member guideway. The other beveled guide-edge 61 of the bushing-flange 58 is engaged by an undercut edge of a wedge-block 63 having its opposite vertical side edge in contact with the recess-shoulder 57. The wedge-block 63 is secured, by screws 64, to the carrier-member 43, with the lower face of the wedge-block spaced from the bottom wall of the carrier-member guideway recess, the wedge-block 63 thereby serving to clamp the flange 58 in different set positions of the bearing-member 59. By releasing the wedge-block 63, the bearing-member 59 may be adjusted diametrically crosswise of the carrier-member 43 from one position, wherein the carrier-member 43 and the bearing-member 59 are concentric, to different set positions wherein the longitudinal axis of the bearing-member 59 is eccentric but parallel to the axis of rotation of the carrier-member 43.

Rotatably journaled in the bearing-member 59 is the upper shaft-section 65 of the loop-taker shaft, said shaft-section 65 being offset laterally from and disposed substantially parallel to the axis of rotation of the lower shaft-section 32. The upper end of the shaft-section 65 is integral with or otherwise suitably carries a loop-taker 66 which, in the present case, is of the conventional vertical-axis rotary hook type. The loop-taker 66 has the usual cup-shaped body provided in the cylindrical side wall thereof with a beak 67 for seizing thread-loops from the endwise reciprocatory and laterally vibratory needle 20, and for casting said thread-loops about a thread-carrier 68 suitably journaled in the loop-taker. It is to be understood, however, that in its broader aspects the present invention is not limited to any specific form of loop-taker. As the loop-taker shaft-section is journaled eccentrically in the carrier-member 43, the loop-taker shaft has imparted thereto translatory lateral movements in a circular orbital path upon rotation of the carrier-member 43. The amplitude of said orbital path may be varied by adjustment of the bearing-member 59 crosswise of the carrier-member 43.

The upper shaft-section 65 is rotated in one-to-one relation with the lower shaft-section 32, i. e., twice for each complete reciprocation of the needle, in any set positions of the shaft-section 65 with respect to the axis of rotation of the lower shaft-section 32. To this end, the hub of the spur-gear 55 secured upon the lower shaft-section 32 is provided with a pair of upwardly open notches 69 alined diametrically of the spur-gear hub. Disposed in the notches 69 are teeth 70 depending from and alined diametrically of a collar 71 which is suitably secured upon an intermediate shaft-section 72; said collar 71 being preferably disposed in engagement with the upper end of the lower shaft-section 32 and in spaced relation to the hub of the spur-gear 55. The intermediate shaft-section 72 is preferably provided with a rounded or tapered lower end 73 which extends into a bore 74 in the upper end of the lower-shaft section 32, thereby to steady the driving connection between the lower and intermediate shaft-sections.

At its upper end, the intermediate shaft-section 72 carries another collar 75; said collar 75 having upwardly extending driving teeth 76 alined diametrically of the collar. The collar-teeth 76 engage notches 77 provided in a collar 78 secured upon the upper shaft-section 65. A washer 79 is preferably interposed between the collar 78 and the lower end of the bearing-member 59, thereby permitting free rotation of the upper shaft-section 65 while holding said shaft-section against upward movement in the bearing-member 59. The upper end of the intermediate shaft-section 72 is preferably also rounded or tapered and extends into a bore 65' in the lower end of the shaft-section 65.

While the loop-taker shaft-sections of the present machine have universal-joint connections of a specific and preferred form as above described, it is to be understood that other forms of universal-joint or flexible shaft connections may be employed for the purpose of rotating the loop-taker with a substantially uniform angular velocity.

The thread-carrier 68 of the loop-taker 66 is restrained against rotation with the loop-taker and, to that end, the thread-carrier 68 is provided with the usual stop-lug or -element 80. The stop-element 80 loosely enters a downwardly open stop-notch or complementary stop-element 81 formed in a horizontally disposed bar 82 of an upstanding stop-member bracket 83. The bracket 83 is cut away to provide a loop-taker clearance opening 84 and a laterally offset foot 85. The bracket-foot 85 is secured by screws 86 upon a bracket-plate 87 having a sleeve-hub 88 pivotally embracing the cylindrical upper portion of the bearing-member 59 above the flange 58 thereof. The bracket-plate is thereby fulcrumed upon the bearing-member 59 coaxially of the loop-taker shaft-section 69, whereby the stop-element 81 moves in an orbital path corresponding substantially to the orbital path of the loop-taker 66. The bracket-plate 87 is provided with a rearwardly extending guide-slot 89 in which is disposed an anchoring pivot-block 90; said pivot-block 90 being carried by a vertically disposed anchor-pin 91 secured by a set-screw 92 in an aperture provided in the stationary loop-taker bracket-lug 41. The bracket-plate 87 is therefore guided by the anchoring pivot-block 90 to maintain the stop-element 81 in cooperative relation with the stop-element 80.

7 during the translatory movements of the loop-taker 66.

The thread-carrier 68 is slightly oscillated in a direction opposite to the direction of rotation of the loop-taker 66 to open the thread-carrier stops for the passage of needle-thread loops. To this end, the thread-carrier 68 is provided with the usual cam-element 93 adapted to be intermittently engaged by a finger 94 of a mechanical-opener device. The finger 94 is carried by the upwardly extending portion of a horizontally vibratory arm 95. The vibratory arm 95 has one end thereof pivotally supported by a vertically disposed pivot-pin 96 carried by the bracket-plate 87. Intermediate its ends, the vibratory arm 95 is pivotally connected to one end of a short pitman 97, of which the opposite end has a strap embracing an eccentric 98 carried by the upper shaft-section 65 of the loop-taker 66 directly below said loop-taker. The pitman 97 is preferably held spaced by a washer 99 from the upper end of the bearing-member 59 and the sleeve-hub 88 of the stop-member bracket-plate. At its upper end, the loop-taker bracket 37 is provided with an upstanding flange 100 surrounding a portion of the mechanical-opener and thread-carrier rotation-restraining mechanisms, said flange 100 functioning primarily as an oil-retaining guard.

10 30 Being mounted upon the translatory bracket-plate 87, and being actuated from the loop-taker shaft-section 65, the thread-carrier performs substantially uniform thread-carrier oscillating movements in different positions of said loop-taker in the orbital path of the latter.

35 The bed-shaft 24 adjustably carries another spiral driving gear 101 spaced from the driving gear 29. The driving gear 101 actuates a left-hand loop-taker mechanism which is adjustably supported in the same manner and is structurally 40 the same as the right hand loop-taker mechanism hereinbefore described. The left-hand loop-taker is complementary to the endwise reciprocatory and laterally vibratory needle 19 in 45 the formation of lock-stitches; the parts of said left-hand loop-taker mechanism, so far as illustrated in the accompanying drawings, being designated by the reference numerals applied to corresponding parts of the right hand loop-taker 50 mechanism. While the present machine contains two needles and two loop-takers, the present invention, in its broader aspects, is not to be considered as limited to two needles, as the loop-taker mechanism herein described may obviously 55 be employed in a single needle sewing machine.

In the present embodiment of the invention, the work is advanced crosswise of the plane of vibration of the needles 19, 20 by a feeding mechanism including a feed-dog 102 of the drop-feed type. The feed-dog 102 operates through a suitably slotted throat-plate 103 secured upon the frame-bed 10, said feed-dog being opposed in its upward movement by the usual spring-depressed presser-foot 104.

60 65 The feed-dog 102 is secured by screws 105 upon a feed-bar 106 intermediate the ends of said feed-bar. In order to impart work-advancing and return movements to the feed-dog 102, one end of the feed-bar 106 is pivotally connected to an upstanding rocker 107 carried by a rock-shaft 108 disposed in parallelism with the bed-shaft 24. The rock-shaft 108 is journaled in suitable bearings provided in the bed-frame 10 and is operatively connected by a pitman 109 to 70 derive actuation from an adjustable eccentric 110

carried by the arm-shaft 17. Feed-lift movements are imparted to the feed-dog 102 from a feed-lift eccentric 111 carried by the bed-shaft 24 and disposed between the driving-gears 29, 101. The feed-lift eccentric 111 is embraced by a strap at the lower end of a pitman 112 having vertically directed endwise movements within the frame-bed 10. At its upper end, the pitman 112 is pivotally connected to the end of the feed-bar 106 opposite its connection with the feed-advance rocker 107.

In the operation of the present machine, each of the endwise reciprocatory needles 19 and 20 is vibrated laterally to penetrate the work at points spaced from each other crosswise of the line of feed of the work, to effect the production of zig-zag stitches. However, the feeding of the work may be omitted, if desired, to effect the production of a group of stitches, as in tacking, button-sewing and like sewing machines. It is immaterial whether the needles are vibrated toward and from each other, or whether they vibrate in unison and, as hereinbefore explained, one of the needles and its complemental loop-taker may be omitted.

The bed-shaft spiral-gear 29 drives the spiral-pinion 33 and thereby rotates the sectional loop-taker shaft 32, 65, 72, at a uniform angular velocity, twice for each rotation of the bed-shaft 24. The loop-taker 66 is thereby rotated twice for each complete needle reciprocation and about an axis which is substantially parallel to the needle. In one rotation of the loop-taker 66, it seizes a loop of thread from its coating needle and casts said loop about the thread-carrier 68, the succeeding rotation of the loop-taker being an idle rotation during which the work is advanced and the needle is shifted laterally while out of the work.

Being journaled eccentrically in the carrier-member 43, the loop-taker 66 while rotating about its own axis is translated laterally and continuously in a circular orbital path defining a field transverse to the needle. The diameter of the circular orbital path of travel of the loop-taker corresponds substantially to the amplitude of lateral vibration of the needle, it being understood that in order to accommodate variations in adjustment of the amplitude of vibration of the needle the diameter of the orbital path of the loop-taker may be correspondingly varied by adjustment of the loop-taker bearing-member 59 crosswise of the axis of rotation of the loop-taker. The vertical-axis loop-taker 66 is so located with respect to the endwise vertically reciprocating needle and the movements of the parts are so coordinated that the loop-taker beak 67 is positioned to seize the thread-loops from the needle at diametrically opposite points in the orbital path of the loop-taker. To this end, the loop-taker 66 is, as usual, rotated twice for each needle reciprocation while said loop-taker is translated laterally in a semi-circular path from one loop-seizing position at one end of a diameter of the orbital path to a succeeding loop-seizing position at the opposite end of said diameter. In order to obtain this timing of the lateral travel of the loop-taker, the carrier-member is rotated by the speed-reducing gears 49, 51, 54 and 55 to transmit to the loop-taker one-half of its circular orbital movement for each complete needle reciprocation.

Inasmuch as the rotations of the loop-taker 66 about its axis 65 and the rotations of the carrier-member 43 are both derived from the shaft-

section 32 which has its axis of rotation coincident with the axis of rotation of the carrier-member 43, the proper timing of the loop-taker with respect to the needle will be maintained regardless of the length of the diameter of the orbital path of movement of the loop-taker.

As the thread-carrier rotation-restraining stop-element 81 and the thread-carrier oscillating-opener-finger 94 are both carried by the pivotally anchored bracket-plate 87 which is fulcrumed coaxially of the loop-taker to partake of the translatory lateral movement of said loop-taker, the stop-element 81 and the opener-finger 94 likewise perform translatory movements such as to maintain them effective in successive stitch-forming cycles of the laterally vibratory needle.

Having thus set forth the nature of the invention what I claim herein is:

1. Loop-taker mechanism for sewing machines, comprising, a rotary loop-taker, means for transmitting to said rotary loop-taker translatory lateral movement in an orbital path, and driving connections for rotating said loop-taker at a uniform angular velocity during the translatory movement of the loop-taker.

2. Loop-taker mechanism for sewing machines having an endwise reciprocatory and laterally vibratory needle, comprising, a rotary loop-taker, means for transmitting to said rotary loop-taker needle-compensating bodily movements in a circular orbital path and at a uniform angular velocity, and driving connections for rotating said loop-taker at a uniform angular velocity during said bodily movements of the loop-taker.

3. Loop-taker mechanism for sewing machines, comprising, a loop-taker, means for imparting needle-thread loop seizing movements to said loop-taker, means for transmitting to said loop-taker bodily movement in an orbital path, and means for varying the amplitude of the orbital path of movement of said loop-taker.

4. Loop-taker mechanism for sewing machines having an endwise reciprocatory and laterally vibratory needle, comprising, a rotary loop-taker, driving connections for rotating said loop-taker, means for transmitting translatory lateral movement to the axis of rotation of said loop-taker in an orbital path in timed relation to compensate for the lateral vibration of said needle, and means for varying the amplitude of the orbital path of compensating movement of the loop-taker.

5. Loop-taker mechanism for sewing machines having an endwise reciprocatory and laterally vibratory needle, comprising, a loop-taker carrying shaft, a loop-taker carried by one end of said shaft, driving connections with the other end of said shaft for imparting needle-thread loop-seizing movements to said loop-taker, and means for transmitting needle-compensating movements to said loop-taker in an orbital path.

6. Loop-taker mechanism for sewing machines, comprising, a rotary loop-taker, a rotary and laterally translatory loop-taker carrying shaft, driving connections with said shaft for rotating said loop-taker at a uniform angular velocity, and driving connections for transmitting laterally translatory movement to said shaft in an orbital path.

7. Loop-taker mechanism for sewing machines having an endwise reciprocatory and laterally vibratory needle, comprising, a rotary loop-taker, a rotary and laterally translatory loop-taker carrying shaft, driving connections with said shaft for rotating said loop-taker at a uniform angular velocity.

lar velocity about an axis substantially parallel to said needle, and driving connections for transmitting laterally translatory movement to said shaft in an orbital path defining a field transverse to said needle.

8. In a sewing machine, a rotary carrier-member, driving connections for rotating said carrier-member, a loop-taker journaled in said carrier-member for rotation about an axis eccentric to the axis of rotation of said carrier-member, whereby translatory movement is imparted to said loop-taker in an orbital path, means providing for adjustment of the eccentricity of said loop-taker with respect to the axis of rotation of said carrier-member, and driving connections for rotating said loop-taker.

9. In a sewing machine, a rotary carrier-member, driving connections for rotating said carrier-member, a bearing-member mounted in said carrier-member for adjustment crosswise of the axis of rotation of said carrier-member, a loop-taker journaled for rotation in said bearing-member, and driving connections for rotating said loop-taker relatively to said carrier-member.

10. In a sewing machine, a rotary carrier-member, driving connections for rotating said carrier-member, a bearing-member mounted in said carrier-member for adjustment crosswise of the axis of rotation of said carrier-member, a rotary loop-taker, a loop-taker carrying shaft journaled for rotation in said bearing-member, and driving connections with said shaft for rotating said loop-taker relatively to said carrier-member.

11. In a sewing machine, a rotary carrier-member journaled for rotation about a stationary axis, driving connections for rotating said carrier-member, said carrier-member having a guideway disposed transverse to the axis of rotation of said carrier-member, a bearing-member adjustably disposed in said guideway, a loop-taker rotatably journaled in said bearing-member, and driving means for rotating said loop-taker at a uniform angular velocity in different set positions of said bearing-member in the guide-way of said carrier-member.

12. In a sewing machine, a carrier-member rotatable about a stationary axis, driving connections for rotating said carrier-member, a bearing-member mounted in said carrier-member for adjustment crosswise of the axis of rotation of the carrier-member, a shaft rotatably journaled in said bearing-member, a loop-taker carried by one end of said shaft, and driving means connected to the other end of said shaft for rotating the loop-taker at a uniform angular velocity in different set positions of said bearing-member in said carrier-member.

13. In a sewing machine, a rotary carrier-member having a stationary axis of rotation, a rotary loop-taker journaled in said carrier-member for bodily lateral movement in an orbital path, a flexibly jointed sectional loop-taker carrying shaft having a shaft-section rotatable about a stationary axis, driving connections with said shaft-section for rotating said loop-taker, and driving connections for rotating said carrier-member.

14. In a sewing machine, a rotary carrier-member having a stationary axis of rotation, a rotary loop-taker journaled in said carrier-member for bodily lateral movement in an orbital path, a flexibly jointed sectional loop-taker rotatable shaft having a shaft-section rotatable about a stationary axis, driving connections with said shaft-section for rotating said loop-taker, and

driving connections with said shaft-section for rotating said carrier-member.

15. In a sewing machine, a sectional loop-taker shaft having a plurality of flexibly jointed shaft-sections, including a driving shaft-section journaled for rotation about a stationary axis and a loop-taker carrying shaft-section journaled for bodily lateral movement, actuating connections with said driving shaft-section for rotating said shaft, and means for transmitting bodily lateral movement in an orbital path to the loop-taker carrying shaft-section.

16. In a sewing machine, a sectional loop-taker shaft having a plurality of flexibly jointed shaft-sections, including a driving shaft-section journaled for rotation about a stationary axis and a loop-taker carrying shaft-section journaled for bodily lateral movement, actuating connections with said driving shaft-section for rotating said shaft, and connections with said driving shaft-section for transmitting bodily lateral movement in an orbital path to the loop-taker carrying shaft-section.

17. In a sewing machine, a sectional loop-taker shaft having a plurality of flexibly jointed shaft-sections, including a shaft-section journaled for rotation about a stationary axis and a loop-taker carrying shaft-section journaled for rotation about an axis which is translatory in a circular orbital path concentric with said stationary axis, means for rotating said shaft, and means for transmitting translatory movement to said loop-taker carrying shaft-section in said orbital path.

18. In a sewing machine, a sectional loop-taker shaft having a plurality of flexibly jointed shaft-sections, including a driving shaft-section journaled for rotation about a stationary axis and a loop-taker carrying shaft-section offset laterally from and disposed substantially parallel to said driving shaft-section, actuating connections with said driving shaft-section for rotating said shaft, and driving connections for transmitting lateral translatory movement to said loop-taker carrying shaft-section.

19. In a sewing machine, a sectional loop-taker shaft having a plurality of flexibly jointed shaft-sections, including a driving shaft-section journaled for rotation about a stationary axis and a loop-taker carrying shaft-section offset laterally from and disposed substantially parallel to said driving shaft-section, adjustable means providing for varying the offset spacing of the axes of rotation of said shaft-sections, actuating connections with said driving shaft-section for rotating said shaft, and connections for transmitting lateral translatory movement to said loop-taker carrying shaft-section in a circular orbital path concentric with said driving shaft-section.

20. In a sewing machine, a rotary loop-taker having a laterally translatory axis of rotation, a rotary carrier-member having a stationary rotation-axis, said loop-taker being rotatably journaled in said carrier-member eccentrically of the axis of rotation of said carrier-member, a rotary actuating element having a stationary axis of rotation coincident with the axis of rotation of said carrier-member, driving connections with said actuating element for rotating said loop-taker at a uniform angular velocity, and driving connections with said actuating element for rotating said carrier-member at a uniform angular velocity less than that of said loop-taker.

21. In a sewing machine having an endwise reciprocating and laterally vibratory needle, a rotary loop-taker complementary to said needle in

the formation of stitches and having a laterally translatory axis of rotation, a rotary carrier-member having a stationary rotation-axis, said loop-taker being rotatably journaled in said carrier-member eccentrically of the axis of rotation of said carrier-member, a rotary actuating element having a stationary axis of rotation coincident with the axis of rotation of said carrier-member, driving connections with said actuating element for rotating said loop-taker twice for each complete reciprocation of said needle, and driving connections with said actuating element for rotating said carrier-member once for two complete reciprocations of said needle.

22. In a sewing machine having an endwise reciprocatory and laterally vibratory needle, a rotary loop-taker complementary to said needle in the formation of stitches and having a laterally translatory axis of rotation, a rotary carrier-member having a stationary rotation-axis, said loop-taker being rotatably journaled in said carrier-member eccentrically of the axis of rotation of said carrier-member, loop-taker rotating means including a shaft-section journaled for rotation about an axis coincident with the axis of rotation of said carrier-member, and a train of speed-reducing gears connecting said shaft-section and said carrier-member for rotating said carrier-member at an angular velocity less than that of said loop-taker.

23. In a sewing machine having an endwise reciprocatory and laterally vibratory needle, a loop-taker supporting bracket, a tubular carrier-member rotatably journaled in said bracket, a flexibly-jointed sectional loop-taker shaft having a shaft-section rotatably journaled in said carrier-member eccentrically of the axis of rotation of said carrier-member, a loop-taker carried by said shaft-section, said shaft extending through said carrier-member and having a driving shaft-section journaled in said bracket for rotation about a stationary axis coincident with the axis of rotation of said carrier-member, means connected to said driving shaft-section for rotating said shaft, and a train of gears connected to said driving shaft-section for rotating said carrier-member.

24. In a sewing machine having an endwise reciprocatory and laterally vibratory needle, a loop-taker supporting bracket, a carrier-member rotatably journaled in said bracket, a rotary loop-taker journaled eccentrically in said carrier-member, means for rotating said loop-taker including a shaft-section having an axis of rotation coincident with the axis of rotation of said carrier-member, a counter-shaft rotatably journaled in said bracket, intermeshing gears connecting said shaft-section and counter-shaft, and intermeshing gears connecting said counter-shaft and carrier-member.

25. In a sewing machine having an endwise reciprocatory and laterally vibratory needle, a loop-taker supporting bracket, a carrier-member rotatably journaled in said bracket, a bearing-member mounted in said carrier-member for adjustment crosswise of the axis of rotation of said carrier-member, a loop-taker rotatably journaled in said bearing-member, means for rotating said loop-taker including a shaft-section journaled in said bracket and having an axis of rotation coincident with the axis of rotation of said carrier-member, and a train of speed-reducing gears connecting said shaft-section and said carrier-member.

26. In a sewing machine having an endwise reciprocatory and laterally vibratory needle, a stationary loop-taker bracket, a rotary and laterally translatory loop-taker journaled in said bracket and complementary to said needle in the formation of lock-stitches, means for rotating said loop-taker, means for transmitting to said loop-taker translatory lateral movement relative to said bracket in an orbital path to compensate for the lateral vibration of said needle, a thread-carrier journaled in said loop-taker, and complementary stop-elements for restraining said thread-carrier against rotation with said loop-taker.

27. In a sewing machine having an endwise reciprocatory and laterally vibratory needle, a rotary loop-taker complementary to said needle in the formation of lock-stitches, a stationary loop-taker supporting bracket, means for rotating said loop-taker, means for transmitting to said loop-taker translatory lateral movement relative to said bracket in an orbital path to compensate for the lateral vibration of said needle, a thread-carrier journaled in said loop-taker, and means for restraining said thread-carrier against rotation with said loop-taker comprising a stop-element disposed for engagement with said thread-carrier, said stop-element being supported for movement relative to said bracket in an orbital path corresponding substantially to the orbital path of said loop-taker.

28. In a sewing machine having an endwise reciprocatory and laterally vibratory needle, a rotary loop-taker complementary to said needle in the formation of lock-stitches and having a laterally translatory axis of rotation, means for rotating said loop-taker, means for imparting translatory movement in an orbital path to said loop-taker to compensate for the lateral vibration of said needle, a thread-carrier journaled in said loop-taker, and means for restraining said thread-carrier against rotation with said loop-taker including a thread-carrier engaging stop-element fulcrumed substantially coaxially of said loop-taker for translatory movement therewith, and pivotal anchoring means confining said stop-element to oscillatory movement about the translatory axis of rotation of said loop-taker.

29. In a sewing machine having an endwise reciprocatory and laterally vibratory needle, a stationary loop-taker bracket, a carrier-member rotatably journaled in said bracket, a loop-taker journaled eccentrically in said carrier-member for translatory movement in a circular orbital path, means for rotating said loop-taker, means for rotating said carrier-member, a thread-carrier journaled in said loop-taker and restrained against rotation therewith, a rotation restraining stop-element in engagement with said thread-carrier, said stop-element being fulcrumed substantially coaxially of said loop-taker for translatory movement therewith, and stop-element anchoring means carried by said loop-taker bracket confining said stop-element to operative engagement with said thread-carrier throughout the orbital movement of said loop-taker.

30. In a sewing machine including an endwise reciprocatory and laterally vibratory needle, a rotary loop-taker having translatory lateral movements in an orbital path to compensate for the lateral vibration of the needle, and a thread-carrier journaled in and restrained against rotation with said loop-taker, the improvement which

consists in the provision of opener means for slightly oscillating said thread-carrier in a direction opposite to the direction of rotation of said loop-taker, said opener means including a thread-carrier engaging finger performing substantially uniform thread-carrier oscillating movements in different positions of said loop-taker in its orbital path, and means for actuating said finger.

31. In a sewing machine including an endwise reciprocatory and laterally vibratory needle, a rotary loop-taker having progressively-translatory lateral movements in an orbital path to compensate for the lateral vibration of the needle, and a thread-carrier journaled in and restrained against rotation with said loop-taker, the improvement which consists in the provision of opener means for slightly oscillating said thread-carrier in a direction opposite to the direction of rotation of said loop-taker, said opener means comprising a vibratory thread-carrier engaging finger, and means for shifting the field of effective vibration of said finger to correspond with the progressively changing positions of said thread-carrier due to the orbital movement of said loop-taker.

32. In a sewing machine having an endwise reciprocatory and laterally vibratory needle, a stationary loop-taker bracket, a loop-taker rotatably journaled in and having translatory lateral movement relative to said bracket, means for rotating said loop-taker, means for transmitting said translatory movement to said loop-taker in an orbital path to compensate for the lateral vibration of said needle, a thread-carrier journaled in and restrained against rotation with said loop-taker, a bracket-plate supported for translatory movement with said loop-taker, a thread-carrier oscillating opener-finger pivotally supported upon said bracket-plate, and means for vibrating said opener-finger a plurality of times in each orbital movement of said loop-taker.

33. In a sewing machine having an endwise reciprocatory and laterally vibratory needle, a rotary loop-taker, means for rotating said loop-taker, means for transmitting translatory movement to said loop-taker transversely of its axis of rotation and in an orbital path to compensate for the lateral vibration of said needle, a thread-carrier journaled in and restrained against rotation with said loop-taker, a bracket-plate fulcrumed coaxially of said loop-taker for translatory movement therewith, means anchoring said

bracket-plate for oscillatory movement about the translatory axis of rotation of said loop-taker, a thread-carrier oscillating opener-finger pivotally supported upon said bracket-plate, and means for vibrating said opener-finger a plurality of times in each orbital movement of said loop-taker.

34. In a sewing machine having an endwise reciprocatory and laterally vibratory needle, a stationary loop-taker bracket, a carrier-member rotatably journaled in said bracket, means for rotating said carrier-member, a rotary loop-taker journaled eccentrically in said carrier-member for translatory movement in a circular orbital path, means for rotating said loop-taker, a thread-carrier journaled in said loop-taker, a bracket-plate fulcrumed for translatory movement with said loop-taker, means anchoring said bracket-plate for oscillatory movement about the fulcrum-axis thereof, a stop-element supported by said bracket-plate and disposed in engagement with said thread-carrier for restraining said thread-carrier against rotation with said loop-taker, an opener-finger pivotally supported upon said bracket-plate for engagement with said thread-carrier, thereby to oscillate said thread-carrier in a direction opposite to the direction of rotation of said loop-taker, and actuating connections for vibrating said opener-finger.

35. In a sewing machine having an endwise reciprocatory and laterally vibratory needle, a rotary and laterally translatory loop-taker complementary to said needle in the formation of stitches, driving connections for rotating said loop-taker at a uniform angular velocity a plurality of times for each reciprocation of said needle, and means for transmitting to said rotary loop-taker translatory lateral movement in an orbital path in timed relation to compensate for the lateral movements of said needle.

36. In a sewing machine having an endwise reciprocatory and laterally vibratory needle, a rotary and laterally translatory loop-taker complementary to said needle in the formation of stitches, driving connections for rotating said loop-taker at a uniform angular velocity in successive rotations of said loop-taker, and means for transmitting to said loop-taker translatory lateral movement in an orbital path in timed relation to compensate for the lateral movements of said needle.

ARTHUR N. HALE.
